UNITED STATES PATENT OFFICE.

RAPHOEL COOK AND OTTO LINDLEY, OF COSBY, MISSOURI.

PUMP.

1,133,009.

Specification of Letters Patent. Patented Mar. 23, 1915.

Application filed April 15, 1914. Serial No. 832,087.

To all whom it may concern:

Be it known that we, RAPHOEL COOK and OTTO LINDLEY, citizens of the United States, residing at Cosby, in the county of Andrew 5 and State of Missouri, have invented certain new and useful Improvements in Pumps, of which the following is a specification.

Our invention relates to improvements in 10 lift and force pumps, and particularly to that type in which a piston is reciprocable within an open top cylinder, during a pumping operation, to forcibly discharge the water acted upon through a suitable stand 15 pipe which, in the present instance, also acts or serves as the piston rod.

The invention consists in the construction and arrangement of parts as will be hereinafter fully described and claimed.

20 In the said description, reference will be had to the accompanying drawings wherein like characters denote like or corresponding parts throughout the several views, and in which:—

25 Figure 1 is a side elevation of the pump, the well or receptacle from which the liquid is forced being shown in section; Fig. 2 is a similar view, the piston having been forced to the end of its downward stroke; 30 Fig. 3 is a top plan view of the pump; Fig. 4 is an enlarged longitudinal sectional view of the cylinder and piston; and Fig. 5 is a detail perspective view illustrating the manner in which the platform or pedal is supported.

35 Referring now to the drawings by numerals, 1 designates the well or receptacle from which the water or other liquid acted upon is drawn. Suspended within the said well 40 and a suitable distance beneath or below the normal water line thereof, is an open top cylinder 2 within which a piston designated as an entirety by the numeral 3 operates. Any suitable means such as the hanger bars 45 4 may be provided to suspend the cylinder in the manner above set forth, the said bars, as shown, being attached to the well top designated 5. Threaded, as indicated at 6 to the piston 3 is a stand or discharge pipe 50 7, said pipe extending upwardly through the well top 5 and terminating in a suitable spout 8 terminating at a point directly over and above a suitable trough 9.

55 Pivots connected as at 10 to the free end of the lift pipe 7 is a link or connection

11, the opposite end of which is in turn pivoted as at 12 to an operating lever 13 fulcrumed intermediate its ends at a point 14, a suitable stand 15 acting as a support for the lever at its fulcrumed point. The opposite end of the lever 13 from that pivoted to the link 11 has secured thereto as indicated at 16 helical springs 17, the opposite ends of which are attached in any suitable manner to the ground.

60 Ports 18 are formed within the piston 3, preferably at diametrically opposite points, which ports, during the downward stroke of the piston, are automatically closed by flap valves 19 pivoted as at 20 to the under 65 side of the piston. Upon the upward stroke of the piston 3 valves 19 automatically open while the valve 21 pivoted as at 22 within the pipe stand 7, automatically closes, this 70 operation, as is obvious, providing for a 75 refilling of that portion of the cylinder below the piston 3.

75 As a means whereby the lever 13 may be oscillated, a platform 23 has been provided, 80 said platform being hingedly connected as at 24 to the base of the support 15, its free end being pivoted as at 25 to a suitable frame 26 in turn connected as at 27 to the lever 13 at a point adjacent the pivot 85 point 12.

85 Operation of the pump is as follows: When it is desired that the liquid acted upon be pumped, pressure is brought to bear upon platform or pedal 23, causing lever 13 to be oscillated and stand pipe 7 to 90 be forced downwardly. The said pipe 7 being rigid with piston 3, the latter executes its downward stroke, forcing water within the cylinder and below the piston to open valve 21 and flow through the said pipe 7 95 and spout 8 into the trough or receptacle 9. By relieving the platform or pedal 23 of the pressure, springs 17 will return lever to its normal position indicated in Fig. 1, allow pipe 7 to move upwardly and piston 3 to 100 execute its upward stroke, in which event valve 21 will automatically close and the valves 19 automatically open to permit a refilling of that portion of the cylinder below the piston 3.

105 A suitable bearing such as is indicated at 28 may be arranged within the cylinder to maintain the pipe stand 7 concentrically therein.

110 From the foregoing, taken in connection

with the accompanying drawings it is apparent that operation is effected by pressure upon platform 23; that the operation of the several valves is positive and automatic; and 5 that by the provision of the springs 17, piston 3 is forced to execute its upward stroke to provide for continued operation of the pump. Attention is also called to the fact that springs 17 may be disconnected, 10 and operating lever 13 actuated by hand and irrespective of pressure upon platform 23.

In reduction to practice, we have found that the form of our invention, illustrated in the drawings and referred to in the above 15 description, as the preferred embodiment, is the most efficient and practical; yet realizing that the conditions concurrent with the adoption of our device will necessarily vary, we desire to emphasize the fact that various 20 minor changes in details of construction, portion and arrangement of parts may be resorted to, when required, without sacrificing any of the advantages of our invention, as defined in the appended claim.

25 Having thus fully described our invention, what we claim as new and desire to secure by Letters Patent, is:—

In combination with a force pump; actu-

ating means therefor including an upright comprising spaced standards, an elbow 30 mounted on each standard, the respective elbows being arranged to open inwardly, and a connecting bar fitting the respective elbows, the latter serving as bearings therefor, said bar being oscillatable; an operating lever having connection with the bar, said bar acting as a fulcrum for the lever; lateral extensions formed on one end of the lever; a spring having connection with the extension terminals to normally maintain 40 one end of said lever elevated; a treadle hingedly connected to the upright at its base; a connection between the lever and the free end of said treadle to normally maintain the latter in an elevated position; 45 and a connection between the lever and the pump mechanism to actuate the latter through movement of said treadle against tension of the spring aforesaid.

In testimony whereof we affix our signatures in presence of two witnesses.

RAPHOEL COOK.
OTTO LINDLEY.
